PARAFFIN REMOVING DEVICE

Ira A. Miller, Houston, Tex., assignor to Herbert
C. Otis, Dallas, Tex.

Application July 14, 1939, Serial No. 284,417

22 Claims. (Cl. 166—18)

This invention relates to new and useful improvements in paraffin removing devices.

One object of the invention is to provide an improved device for removing paraffin from the walls of a well tubing which is so constructed that it may be run into the well on a flexible line, such as a wire line or cable, and which may be lowered through the upwardly flowing well fluid without materially interfering with said flow.

An important object of the invention is to provide an improved paraffin removing device which may be lowered through the well tubing, or conductor, on a flexible line and which has means for automatically locking or arresting the device against upward movement during the lowering operation, in the event that an excessive well pressure, or a sudden upward surge of the well fluid, occurs, thereby obviating the danger of the device being blown or forced upwardly from the well tubing.

A particular object of the invention is to provide a device, of the character described, which is provided with improved locking means which rides on the wall of the tubing or conductor through which the device is lowered and which is so arranged that no gripping action is had upon downward movement of said means through the tubing, said means being adapted to immediately grip the tubing wall upon upward movement of the device, whereby upward displacement of said device, during the lowering operation, is prevented; said locking means being so constructed that said means may be retracted and held in such retracted position to permit removal of the device from the well tubing, when desired and after the paraffin removing operation is completed.

Another object of the invention is to provide an improved paraffin scraper carrying a tubing gripping device normally in a non-gripping position but sensitively so held, whereby a sudden or excessive upward pressure below the device will cause the actuation of the gripping means to arrest upward movement of said scraper.

Another object of the invention is to provide an improved paraffin removing device which is capable of being lowered into the well tubing on a flexible line to perform the scraping operation and which may also be removed from said tubing on a flexible line, whereby the removal of the paraffin is facilitated and the time and labor required is reduced to a minimum.

A further object of the invention is to provide an improved scraping member for paraffin removing device, which may be lowered through the

well fluid flowing upwardly through the tubing and which is arranged to be rotated by the flowing fluid, whereby a faster lowering of the device, as well as an improved scraping and removing action, is accomplished.

Still another object of the invention is to provide an improved paraffin remover, of the character described, which is suspended from a flexible line and which may have a jarring element interposed between said line and said device, whereby, when necessary, the device may be jarred, or driven downwardly, to aid in lowering the remover through the paraffin zone.

A still further object of the invention is to provide an improved paraffin scraping device having means for forcing the same downwardly through a paraffin zone, said means being releasably connected to the device, together with gripping means, whereby an upward pull upon said means serves to lock said device in the tubing and also releases the connection between said means and said device, thus permitting removal of said means while the device remains locked in the tubing for subsequent removal.

A particular object of the invention is to provide an improved paraffin removing device having retractile gripping means mounted on a support together with a connecting element which is normally and releasably secured to the support and which may be utilized to lower the device through the paraffin zone in a well tubing; said connecting element being constructed so that, upon its being released or disconnected from the support, it will coact with the locking means to effect retraction of said means to permit upward removal of the device from the tubing.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a view, partly in elevation and partly in section, of an improved paraffin removing device, constructed in accordance with the invention and showing the same being lowered through the well tubing.

Figure 2 is an enlarged transverse, vertical, sectional view of the device, illustrating the same locked in position against upward movement within the tubing.

Figure 3 is a view, partly in elevation and partly in section, and illustrating the first step

in the method of removing said device upwardly through the tubing.

Figure 4 is a view, partly in elevation and partly in section, showing the device being removed from said tubing.

Figure 5 is an enlarged, horizontal, cross-sectional view, taken on the line 5—5 of Figure 1.

Figure 6 is an enlarged, horizontal, cross-sectional view, taken on the line 6—6 of Figure 2.

Figure 7 is an enlarged, horizontal, cross-sectional view, taken on the line 7—7 of Figure 2.

Figure 8 is an enlarged, horizontal, cross-sectional view, taken on the line 8—8 of Figure 2.

Figure 9 is an enlarged, horizontal, cross-sectional view, taken on the line 9—9 of Figure 2.

Figure 10 is an enlarged, horizontal, cross-sectional view, taken on the line 10—10 of Figure 2.

Figure 11 is a view, similar to Figure 2, of a modified form of the invention, with the parts in their respective positions during the lowering operation.

Figure 12 is a similar view, illustrating the device being removed from the tubing, and

Figure 13 is a view, partly in elevation and partly in section, showing a modified form of scraping element attached to the lower end of the device.

In the drawings, the numeral 10 designates an elongate mandrel having an axial bore 11 extending therethrough. The upper portion of the outer surface of the mandrel is substantially cylindrical and a slip supporting sleeve 13 is slideable longitudinally on this portion. The sleeve is formed with an outwardly directed, annular flange 14 at its upper end and an external collar 15 is preferably made integral with its lower end. The collar has a plurality of radial, T-shaped slots 16 therein, which slots are spaced equidistant therearound and the upper ends of gripping elements 17, which upper ends are also T-shaped (Figure 4), are inserted within said slots. A retaining ring 18, which fits within an annular groove formed in the collar, surrounds said collar and prevents outward displacement of the gripping elements from said slots. Manifestly, the gripping elements are suspended from the sleeve 13 and are movable radially with relation to the mandrel. For limiting the movement of the sleeve on the mandrel, the latter is formed with an external flange 19, preferably integral therewith. As is clearly shown in Figure 2, this flange is slotted to permit the gripping elements 17 to extend therethrough. A confining ring 20 surrounds the flange and confines the elements within the slots of said flange, whereby said gripping elements are retained in close proximity to the outer surface of the mandrel. As is clearly shown in Figure 8, the gripping elements are spaced from each other, whereby vertical fluid passages F are formed therebetween to permit a free and unrestricted flow past the mandrel.

Immediately below the flange 19 the surface of the mandrel is flared or inclined outwardly to form a slip expanding portion 21. Each gripping element 17 includes an arcuate slip 22 at its lower end and the inner surface of the slips engage and ride upon the inclined surface 21 of the mandrel. The outer surface of each slip is formed with gripping teeth 23 which are adapted to engage the inner wall of the well tubing A to prevent upward displacement or movement of the slips and mandrel. When the slips 22 are at the upper end of the inclined portion 21 (Figure

4), and immediately below the flange 19, they are retracted and out of engagement with the tubing wall; however, movement of the mandrel upwardly with relation to the slips causes the outward radial movement thereof to the position shown in Figures 1 to 3, whereby said slips engage the tubing wall; in such position, the mandrel cannot be displaced upwardly within the tubing. Vertical grooves are formed in the outer surface of each slip and extend throughout the length thereof to provide additional fluid passages.

The upper end of the bore 11 of the mandrel 10 is enlarged as shown at 24 and receives a reduced shank 25, which is formed on the lower end of a cylindrical rod or connecting element 26. The shank is releasably connected to the mandrel by a frangible shear pin 27, which extends through a diametrically disposed opening 25' in the shank and through radial openings 28 formed in the mandrel. The upper end of the rod or connecting element 26 has a fishing neck 29 preferably formed integral therewith, and as is clearly shown in Figure 2, the lower end of the fishing neck has a larger diameter than the external diameter of the rod, whereby an external annular shoulder 30 is formed therebetween. A coiled spring 31 surrounds the rod or connecting element 26 and has its lower end engaging the upper end of the sleeve or slip carrier 13. The upper end of the coiled spring 31 abuts the underside of the shoulder 30 and is secured to the rod or connecting element by means of a suitable screw 32, which screw is secured within a radial threaded opening 33 formed in the element. The coiled spring constantly exerts its force to urge the slip carrier and the slips carried thereby downwardly with relation to the mandrel 10.

The upper end of the fishing neck 29 is formed with an upwardly extending connecting pin 34 which is provided with external screw threads and the lower end of a suitable jar device 35 is threaded onto this pin. The jar may be of any suitable construction and is shown as comprising a stationary member 36 which is inter-connected with an upper member 37 in the usual manner. The upper member is movable through a slot 36' formed in the lower member, whereby a jarring or hammering action may be imparted to said lower member in the usual manner. A weight 38 is coupled to the upper end of the jar 35 and has a wire line or cable socket 39 connected to its upper end. A wire line, cable, or other flexible line, 40 has its lower end connected to the socket 39 and its upper end extends to the surface of the well, whereby the device may be lowered through the well tubing on said line.

The lower end of the bore 11 of the mandrel is internally screw-threaded as shown at 41, whereby an upwardly extending threaded pin 42, which is formed on a scraper member 43, may be threaded thereinto. The scraper member includes a solid, cylindrical shank 44, which has the pin 42 extending upwardly therefrom. The lower end of the shank is enlarged, as shown in Figure 3, and has a pair of diametrically opposed arms 45 depending therefrom, which arms are arcuate in cross-section and have their lower ends secured to a scraper ring 46. It is desirable that the shank, arms and ring be made integral with each other. Manifestly, since the arms 45 are diametrically opposite each other, the space between said arms forms openings 47, whereby communication between the interior of

the scraper ring 46 and the exterior of the member 43 is established. In this manner, fluid from below the device may freely flow upwardly through the ring and then outwardly through the openings 47 above the member 43. The outer diameter of the scraper ring 46 is slightly less than the bore of the well tubing A and the extreme lower end of said ring is bevelled or inclined outwardly at 48 so as to form an annular cutting edge or point.

The device is particularly adapted to be lowered through the tubing while the well fluids are flowing upwardly therein and during the lowering operation, the parts are in the position shown in Figure 1, the device being suspended from the cable 40. The device is lowered downwardly through the well tubing A and through the well fluids or liquids which are flowing upwardly therethrough. The well fluids freely by-pass the scraper element or member 43 through the ports 47 and then flow upwardly through the fluid passages F which are formed between the gripping elements and thence upwardly through the tubing. During the lowering operation, the arcuate slips 22 are at the lower end of the mandrel in an expanded position and engage the wall surface of the bore of the tubing A, but since said device is moving downwardly, and also due to the disposition of the teeth of the slips, said slips do not grip the wall surface but merely ride therewith. The coiled spring 31, which is exerting its pressure downwardly on the upper end of the slip carrier 13, is relatively light and serves to hold the slips at the lower end of the inclined portion 21 of the mandrel and prevents the frictional engagement of the slips with the tubing wall from moving said slips upwardly as the device is lowered. Thus, during the lowering of the device, the slips and mandrel move as a unit, with the slips in their outer or expanded position.

Since the scraping ring 46 is of substantially the same diameter as the bore of the tubing, it will be manifest that the annular cutting edge of said ring will contact the paraffin which has adhered to the wall of the tubing. This ring will serve to scrape said paraffin from the tubing wall and the loosened paraffin will be carried upwardly through the openings 47 and upwardly past the device by the fluid which is flowing upwardly in the well. Thus, as the device is lowered through the well tubing, the scraping ring 46 serves to efficiently remove the paraffin from the wall of the tubing, and the flowing well fluids are utilized to immediately carry the removed paraffin to the surface. The lowering fluids will also contact the paraffin layer prior to its removal and will aid the scraper to some extent in effecting removal. In the event that there is any tendency of the device to stick or hang during the lowering of the same, the provision of the jar 35, which is connected between the wire line or cable 40 and the cylindrical rod or connecting element 26, permits the device to be forced downwardly through any such obstruction. In this manner, the device may be readily urged downwardly through the paraffin zone in the tubing.

It may occur that during the lowering of the device there may be a sudden upward surge of the well fluid or liquid, or a sudden high pressure may be built up in the tubing. In such event, this pressure would act against the scraper member 43 which is connected directly to the mandrel 10, whereby said mandrel, as well as the entire

device, would be urged upwardly by the pressure. As explained, the slips are at the lower end of the inclined portion of the mandrel in their expanded position in engagement with the tubing wall. Any upward thrust against the mandrel tending to move the mandrel upwardly will result in the slips immediately biting into or gripping the tubing wall. Such gripping of the tubing by the teeth 23 of the slips prevents an upward movement or displacement of the mandrel or of the device. It is noted that the gripping action of the slips will be aided by the coiled spring 31, which is constantly urging said slips downwardly with relation to the mandrel. A continued force exerted against the underside of the mandrel will merely act to force the slips into tighter gripping engagement with the tubing. From the foregoing, it will be seen that in the event of a sudden high pressure below the device, or of a sudden upward surge of the well fluid during the lowering operation, the slips, which are constantly in engagement with the tubing wall, will immediately grip the tubing to arrest upward movement of the device and thereby prevent the same from being blown upwardly from the well tubing.

After the condition which has caused the slips to grip or bite into the tubing has ceased, it is only necessary to jar downwardly on the rod or connecting element 26, whereby the mandrel 10 will be jarred downwardly relative to the slips which are engaging the wall of the tubing. Such downward movement of the mandrel 10 will cause the mandrel to be moved downwardly with relation to the slips so as to move said slips upwardly on the inclined portion 21. The upward movement of the slips on the inclined portion 21 of the mandrel will result in a retraction of said slips to disengage the teeth thereof from their gripping position with the tubing wall, after which the lowering of the device may be continued. As soon as the teeth are disengaged from gripping position and lowering continued, the coiled spring 31 immediately urges the slips downwardly toward the lower end of the inclined portion, whereby said teeth of the slips again ride along on the tubing wall, as has been explained.

After the device has been moved through the paraffin zone in the well tubing A to remove said paraffin from the wall of said tubing, an upward jar is imparted to the mandrel through the jar 35 and rod 26, by manipulating the wire line or cable 40, whereby said mandrel is urged upwardly. Such action results in the teeth of the slips biting into or gripping the tubing wall so as to lock the device against upward movement within the tubing. Continued upward jarring on the wire line or cable 40 will exert sufficient upward force on the rod 26 to shear the frangible pin 27, whereby the jar 35 and rod 26 may be removed from the well tubing, as is shown in Figure 3. Since the coiled spring 31 has its upper end secured to the rod or element 26, said coiled spring will be removed therewith.

After the removal of the jar and rod, a suitable fishing or removing tool may be lowered through the well tubing on a wire line so that its gripping elements 49 (Figure 4) may be engaged beneath the shoulder 14 on the upper end of the slip carrying sleeve 13. This tool may include a jar (not shown) so that the mandrel may be jarred downwardly with relation to the slips to release the latter. The line and fishing tool are then raised, whereby the sleeve 13 and gripping

elements 17 are raised with relation to the mandrel 10. The slips move upwardly on the inclined portion 21 until they abut the extending shoulder 19 on the mandrel. In this position, as is clearly shown in Figure 4, the slips are retracted and a continued upward movement will result in a removal of the device from the well tubing A. Thus, it will be seen that the device may be readily removed from the tubing by means of a wire line or cable.

From the foregoing, it will be seen that a simple and effective paraffin removing device is provided. The device may be readily run into and removed from the well on a wire line, whereby the time and labor for each run is minimized. During the lowering operation, the slips 22 are in their expanded position but the arrangement is such that no gripping of the tubing by said slips occurs. In case of an unforeseen condition resulting in an upward force being exerted below the device, said slips immediately automatically bite into or grip the tubing wall to arrest upward movement and thereby prevent blowing out of said device. The arrangement permits the slips to be disengaged from their gripping position to continue the lowering operation after the high pressure or other condition which creates the force below the device ceases. After the run is completed and the paraffin has been removed, the device may be readily removed by means of a wire line after the jar 35 and the connecting rod 26 have been disconnected from the mandrel by shearing the pin 27.

It may not be desirable to remove the jar 35 and connecting element 26 separately from the mandrel and slip assembly, as is the case in the form shown in Figures 1 to 10. In order to permit the removal of all of the parts as a single and complete assembly, the device may be constructed as shown in Figures 11 and 12. In this form of the invention, the mandrel 10 is constructed in the same manner and has the paraffin scraping element 43 threaded into its lower end. The gripping elements 17 are mounted on the mandrel so as to move vertically with relation thereto and, instead of being carried by the slip carrying sleeve 13, said slips are supported by an elongate slip supporting sleeve 13a. The lower end of this sleeve is slidable on the upper portion of the mandrel and is provided with radial T-shaped slots 16a similar to the slots 16 in the sleeve 13.

The sleeve 13a is of sufficient length to receive a connecting rod or element 26a, which is similar in construction to the rod 26 in the first form. The element 26a is provided with a reduced shank 25a which is insertable within the upper end of the bore of the mandrel 10 and is connected thereto by the shear pin 27. An external, annular flange or collar 60 is preferably formed integral with the connecting rod 26a and this collar is disposed within the sleeve 13a, having a slightly smaller diameter than said sleeve. The coiled spring 31 is confined between the collar 60 and an internal shoulder 61 which is formed within the bore of the sleeve 13a near the lower end thereof. The spring 31 constantly exerts its force to urge the slip carrying sleeve 13a downwardly so as to maintain the slips 22 at the lower end of the mandrel 10.

The upper end of the sleeve 13a is closed by an annular cap or collar 62 which is threaded into the upper end of the sleeve and which surrounds the extended upper end of the connecting element 26a. The extreme upper end of the

element 26a is formed with a threaded pin 63 which is connected to the lower end of the jar 35.

The operation of this form, during the lowering of the device through the paraffin zone, is substantially the same as that of the form shown in Figures 1 to 10. During such lowering, the parts are in the position shown in Figure 11 and the slips 22 are lowered on the mandrel 10 and ride on the wall of the tubing, said slips being held in this position by the coiled spring 31. At this time, the external collar 60 on the connecting element 26a is spaced from the lower end of the closure cap or collar 62. Any sudden upward force below the device will immediately cause the teeth 23 of the slips 22 to engage the tubing wall and thereby arrest upward displacement of the device, as has been explained. When the device has been locked against upward movement and the force therebelow ceases, the jar 35 is utilized to jar downwardly on the mandrel 10 and release the slips from their gripping position to permit continued lowering of the device.

After the paraffin removing operation has been completed and it is desired to remove the form shown in Figures 11 and 12 from the tubing, it is only necessary to pull upwardly on the wire line or cable carrying the device, whereby an upward pull is transmitted to the mandrel 10 through the jar 35 and connecting element 26a. This causes the teeth of the slips to grip the tubing wall and arrest further upward movement of the device. Upward jarring on the connecting element 26a may be produced by manipulating the wire line and such upward jarring will shear the pin 27 to disconnect the element 26a from the mandrel. A downward jar is then imposed on the mandrel 10 through the jar 35 and connecting element 26a and such jar moves the mandrel downwardly with relation to the slips until the flange 19 strikes the upper end of the slips. In such position, the slips are retracted and by exerting an upward pull on the line, the entire device may be removed from the tubing. It is manifest that in this form of the invention, it is not necessary to completely remove the jar 35 and connecting element separately from, and prior to, the removal of the mandrel and slip assembly. Therefore, it is possible to remove the entire device with one lifting operation.

It is pointed out that any suitable scraping member which will efficiently remove the paraffin from the tubing wall may be employed and, in Figure 13, a modified form of scraping member has been shown. This scraping member includes an elongate curved blade 58, which is reduced toward its lower end, the upper end of said blade being secured to a sleeve 51. The sleeve is rotatable on a shaft 52 which depends from a coupling element 53, said element being threaded into the lower end of the mandrel 10. The mounting of the sleeve 51 on the shaft 52 is clearly shown in Figure 13 and said shaft is provided with a spacer block 54 which is secured to its lower end and which is insertable within the sleeve 51. Suitable bearings 55 are interposed between the lower end of the block 54 and the bore of the sleeve.

An upper bearing assembly 56 is mounted on the block 54 and within the bore of the sleeve, said bearing assembly being retained in position by a flanged collar or gland 57 which is threaded into the upper end of the sleeve and which surrounds the shaft. With the above arrangement, it will be manifest that the sleeve 51 which carries the elongate curved scraper blade 58 is freely

rotatable on the shaft 52. Since the shaft depends from the coupling 53 which is secured to the mandrel 10, it will be obvious that the scraper blade 50 is freely rotatable with relation to the mandrel.

The operation of this form of the invention is substantially the same as the form hereinbefore described, with the exception that the blade 50 rotates as the device is lowered through the paraffin zone. Such rotation is caused by the flowing fluid within the well tubing A striking the curved blade and rotating the same. This arrangement increases the efficiency of the removal of the paraffin as the blade not only scrapes the wall of the tubing, but also directs the fluid into direct contact with said wall, whereby a scouring action is obtained. Manifestly, the flowing fluid serves to immediately carry the removed paraffin to the surface. It is obvious that either form of scraper member may be employed with any of the structures herein described. In all cases, the slips are in a position contacting the tubing wall during the lowering operation and immediately grip the tubing to arrest upward displacement of the device when an excessive upward force occurs below the device.

The foregoing description of the invention is explanatory thereof and various changes in the size, shape and materials, as well as in the details of the illustrated construction, may be made, within the scope of the appended claims, without departing from the spirit of the invention.

What I claim and desire to secure by Letters Patent is:

1. A paraffin removing device including, a support, a scraping member carried by the support for removing paraffin from a tubular conductor as the device is lowered therethrough, and means on the support arranged to lock the device against upward movement in the conductor in the event an upward force is exerted against the lower end of the device, whereby said device is prevented from being forced upwardly and out of the conductor during the lowering operation.

2. A paraffin removing device adapted to be lowered through a well tubing and including, a support, a scraping member carried by the support for removing the paraffin from the wall of the tubing as the same is lowered therethrough, radially movable gripping elements on said support normally in a non-gripping position to permit lowering of the support and scraping member, and means for causing the gripping elements to grip the wall of the tubing in the event the support is urged upwardly, whereby upward displacement of the device from the well tubing during the lowering operation is prevented.

3. A paraffin removing device adapted to be lowered through a well tubing and including, a support, a scraping member carried by the support for removing the paraffin from the wall of the tubing as the same is lowered therethrough, retractile gripping elements on said support normally in a non-gripping position permitting lowering of the support and scraping member, the gripping elements being arranged to immediately grip the wall of the tubing in the event the support is urged upwardly, whereby upward movement of the device is arrested, and means for retracting said gripping elements from their gripping position to permit continued lowering of the device.

4. A paraffin removing device adapted to be lowered through a well tubing and including, a

support, a scraping member carried by the support for removing the paraffin from the wall of the tubing as the same is lowered therethrough, movable gripping elements on said support normally in a position engaging the tubing without gripping the same to permit lowering of the support and member, means for causing the gripping elements to bite into and grip the wall of the tubing in the event the support is urged upwardly, whereby upward displacement of the device during the lowering operation is prevented, and means for retracting said gripping elements and for holding the same in a retracted position to permit removal of the device from the well tubing.

5. A paraffin removing device adapted to be lowered through a well tubing including, a mandrel, means for connecting the mandrel to a flexible line by which said mandrel may be lowered through the tubing, a scraping member carried by the mandrel for removing the paraffin from the tubing as the mandrel is lowered therethrough, gripping means slidable on the mandrel and normally in a non-gripping position to allow lowering thereof, and means on the mandrel coacting with said gripping means for urging and holding the same in gripping position upon relative upward movement of said mandrel, whereby upward displacement of the device in the tubing is prevented in the event the mandrel is urged upwardly during the lowering operation.

6. A paraffin removing device adapted to be lowered through a well tubing including, a mandrel, means for connecting the mandrel to a flexible line by which said mandrel may be lowered through the tubing, a scraping member carried by the mandrel for removing the paraffin from the tubing as the mandrel is lowered therethrough, gripping means slidable on the mandrel and normally in a non-gripping position to allow lowering thereof, means on the mandrel coacting with said gripping means for urging the same into gripping position upon relative upward movement of said mandrel, whereby upward displacement of the device is prevented in the event the mandrel is urged upwardly during the lowering operation, and a jarring device interposed between the mandrel and flexible line for imparting a downward movement to the mandrel to move the same downwardly relative to the gripping means to release said means and permit continued lowering of the device.

7. A paraffin removing device adapted to be lowered through a well tubing including, a mandrel, means for connecting the mandrel to a flexible line by which said mandrel may be lowered through the tubing, a scraping member carried by the mandrel for removing the paraffin from the tubing as the mandrel is lowered therethrough, gripping means slidable on the mandrel and normally in a non-gripping position to allow lowering thereof, means on the mandrel coacting with said gripping means for urging the same into gripping position upon relative upward movement of said mandrel, whereby upward displacement of the device is prevented in the event the mandrel is moved upwardly during the lowering operation, and means for retracting the gripping means and for holding the same in a retracted position, whereby the device may be removed from the well.

8. A paraffin removing device adapted to be lowered through a well tubing including, a mandrel, means for connecting the mandrel to a flexible line by which said mandrel may be lowered

through the tubing, a scraping member carried by the mandrel for removing the paraffin from the tubing as the mandrel is lowered therethrough, gripping means slidable on the mandrel and normally in a non-gripping position to allow lowering thereof, means on the mandrel coaxing with said gripping means for urging the same into gripping position upon relative upward movement of said mandrel, whereby upward displacement of the device is prevented in the event the mandrel is urged upwardly during the lowering operation, a jarring device interposed between the mandrel and flexible line for imparting a downward movement to the mandrel to move the same downwardly relative to the gripping means to release said means and permit continued lowering of the device, a connecting element interposed between the flexible line and mandrel, a shear pin connecting the element and the mandrel, whereby said element may be removed from the mandrel by shearing said pin, and means adapted to be lowered through the tubing and engageable with the gripping means for retracting said means to permit removal of the device from the well.

9. A paraffin removing device adapted to be lowered through a well tubing and including, a support, an annular scraper having a sharp cutting edge carried by the support for removing the paraffin from the wall of the tubing as the same is lowered therethrough, expandible gripping elements on said support normally in an expanded and non-gripping position to permit lowering of the support and scraping member, and means for effecting the gripping action of the elements with the wall of the tubing in the event the support is urged upwardly, whereby upward displacement of the device during the lowering operation is prevented.

10. A paraffin removing device adapted to be lowered through a well tubing and including, a support, a rotatable scraping element carried by the support for removing the paraffin from the wall of the tubing as the same is lowered therethrough, expandible gripping elements on said support normally in an expanded and non-gripping position to permit lowering of the support and scraping member, and means for effecting the gripping action of said elements with the wall of the tubing in the event the support is urged upwardly, whereby upward displacement of the device during the lowering operation is prevented.

11. A paraffin removing device adapted to be lowered through a well tubing and including, a support, a rotatable scraping element having a curved scraping blade which is rotated by the well fluids contacting the same, said element being carried by the support for removing the paraffin from the wall of the tubing as the same is lowered therethrough, expandible gripping elements on said support normally in an expanded and non-gripping position to permit lowering of the support and scraping member, and means for effecting a gripping action of the elements with the wall of the tubing in the event the support is urged upwardly, whereby upward displacement of the device during the lowering operation is prevented.

12. A paraffin removing device for wells including, a support, scraping means carried by said support, tubing gripping means movably mounted on the support and arranged to arrest upward movement of the device in the event an excessive pressure occurs therebelow, a jarring

device for forcing the support downwardly through an accumulation of paraffin, and a frangible connection between the support and the jarring device, whereby said device may be disconnected from the support and removed individually from the well.

13. A paraffin removing device adapted to be lowered through a well tubing and including, a support, a scraping member carried by the support for removing the paraffin from the wall of the tubing as the same is lowered therethrough, the scraping member having a relatively large by-pass opening to permit a substantially unrestricted flow of fluid past said means as the device is lowered through a well, expandible gripping elements on said support normally in an expanded and non-gripping position to permit lowering of the support and scraping member, and means for effecting a gripping action of the elements with the wall of the tubing in the event the support is urged upwardly, whereby upward displacement of the device from the well tubing during the lowering operation is prevented.

14. A paraffin removing device adapted to be lowered through a well tubing and including, a support, a scraping member carried by the support for removing the paraffin from the wall of the tubing as the same is lowered therethrough, radially movable gripping elements on said support normally in a non-gripping position to permit lowering of the support and scraping member, by-pass means on the device for by-passing fluid thereby so as to allow lowering of the device through upwardly flowing well fluid, and means for causing the gripping elements to grip the wall of the tubing in the event the support is urged upwardly, whereby upward displacement of the device from the well tubing during the lowering operation is prevented.

15. A paraffin removing device for wells including, a support, scraping means carried by said support, tubing gripping means movably mounted on the support and arranged to permit lowering of the device and to assume a gripping position upon a relative upward movement of the support, and lowering means releasably connected to the support for moving said support downwardly through an accumulation of paraffin, said last named means being adapted to coat with the tubing gripping means when disconnected from the support, whereby said lowering means may be employed to retract the gripping means and raise the device from the well.

16. A paraffin removing device for wells including, a support, scraping means carried by said support, tubing gripping means movably mounted on the support and arranged to permit lowering of the device and to assume a gripping position upon the occurrence of an excessive pressure below the device, whereby upward displacement of said device is prevented, an elongate connecting element having its lower end releasably connected to the support, which is suspended therefrom during the lowering operation, and means extending upwardly from the tubing gripping means and arranged to coat with the connecting element when the latter is disconnected from the support, whereby said element may be utilized to retract the gripping means and to lift the device from the well.

17. A paraffin removing device including, a support, a scraping member carried by the support for removing the paraffin from a well pipe as the device is lowered therethrough, expandible gripping means on the support disposed to

lock the device against upward movement in the pipe in the event an upward force is exerted on the device, a sleeve slidable on the support and having the gripping means mounted thereon, a supporting rod detachably fastened to the upper end of the support and extending through the sleeve, said rod being arranged to co-act with the sleeve when detached from the support to effect removal of the device by an upward movement of the rod.

18. A paraffin removing device including, a support, a scraping member carried by the support for removing the paraffin from a well pipe as the device is lowered therethrough, expandable gripping slips slidable on the support and disposed to lock the device against upward movement in the pipe in the event an upward force is exerted upon the device, a supporting rod detachably secured to the support and extending upwardly therefrom, a sleeve surrounding said rod and slidably relative thereto, said sleeve having the gripping slips suspended therefrom, resilient means associated with the rod and sleeve for urging the sleeve and slips carried thereby downwardly of the support toward a gripping position, means for detaching the rod from the support upon an upward pull on said rod, and means on said rod adapted to co-act with the sleeve when said rod is disconnected from the support for imparting an upward movement to the sleeve upon an upward movement of the rod.

19. A paraffin removing device for wells adapted to be lowered through the tubing while well fluids are flowing upwardly therein which includes, the combination of a longitudinal support, scraping means carried by said support, means for suspending the support while it is

being raised and lowered in the well, means connected in the suspending means actuatable for positively forcing said support downwardly to force the scraper through an accumulation of paraffin, tubing gripping means movable independently of the support and the suspending means for anchoring the device in the tubing against upward displacement in the tubing by the well fluids, and means for releasably connecting the support and said support-forcing means.

20. A paraffin scraper as set forth in claim 19 wherein the said support-forcing means is connected to the support to be released entirely therefrom and removed from the well so as to leave the support anchored therein.

21. A paraffin scraper as set forth in claim 19 wherein the entire scraper has a relatively large by-pass opening to permit an unrestricted flow of well fluid thereby as the device is lowered into the well, and a frangible connection between the support and the support-forcing means terminating short of the tubing gripping means.

22. A paraffin removing device for wells adapted to be lowered through the tubing against an upward flow of well fluid under pressure which includes, an elongate support, a paraffin-displacing element carried by the support having a rigid wall scraping edge and also having a well fluid by-passing opening, means for suspending the support while the device is being lowered in the well and while paraffin is being scraped, and tubing-gripping elements free to act independently of the suspending means while the device is being lowered in the tubing to anchor it against upward displacement by the well fluids.
